UNITED STATES PATENT OFFICE.

JOHN BOAG, OF KEARNEY, NEW JERSEY.

LIFE-BOAT LOWERING AND HOISTING APPARATUS FOR USE ON SHIPS.

No. 829,054.

Specification of Letters Patent.

Patented Aug. 21, 1906.

Application filed January 13, 1906. Serial No. 295,845.

To all whom it may concern:

Be it known that I, JOHN BOAG, a citizen of the United States, residing at Kearney, in the State of New Jersey, have invented certain new and useful Improvements in Life-Boat Lowering and Hoisting Apparatus for Use on Ships, of which the following is a specification, such as will enable those skilled in the art to which it appertains to make and use the same.

This invention relates to means or apparatus for lowering and raising life-boats; and the object thereof is to provide an improved apparatus of this class which is simple in construction and operation and which may be used on any kind or class of ships or vessels and by means of which a life-boat may be easily and safely lowered when desired and also as easily and safely raised, a further object being to provide an apparatus of the class specified which may be operated by hand or by mechanical means; and with these and other objects in view the invention consists in an apparatus of the class and for the purpose specified constructed as herein-after described and claimed.

The invention is fully disclosed in the following specification, of which the accompanying drawings form a part, in which the separate parts of my improvement are designated by suitable reference characters in each of the views, and in which—

Figure 1 is an end view of my improved lowering and raising apparatus for life-boats; Fig. 2, an outboard side view thereof; Fig. 3, an inboard side view of the framework or casing of the operative mechanism; Fig. 4, an outboard side view of the framework or casing of the operative mechanism; Fig. 5, a vertical section through said mechanism on the line 5-5 of Fig. 1; Fig. 6, a section on the line 6-6 of Fig. 1; Fig. 7, a section on the line 7-7 of Fig. 4; Fig. 8, a section on the line 8-8 of Fig. 2; Fig. 9, a side view of the support for one of the davits which I employ, and Fig. 10 a view at right angles to Fig. 9.

In the drawings forming part of this specification I have shown at *a* in Figs. 1, 2, and 9 a part of the deck of a vessel, and in the practice of my invention I secure thereto or to any suitable support placed thereon transversely arranged brackets *b*, in which is mounted a longitudinally-arranged davit-shaft *b*², provided, preferably, centrally thereof with a worm-gear *b*³, and arranged transversely of the shaft *b*² is a power-shaft *b*⁴, pro-

vided with a worm *b*⁵, which meshes with the worm-gear *b*³, these parts being clearly shown in Figs. 1, 2, 7, and 8.

Rigidly connected with the opposite end 60 portions of the shaft *b*² and adapted to turn therewith are davits *c*, the upper and free ends of which are connected by rods *c*², and the end portions of said davits are also provided with blocks *c*³, through which are 65 passed ropes *c*⁴, and in Figs. 1 and 2 I have also shown at *c*⁵ a life-boat provided with blocks *c*⁶, through which the ropes *c*⁴ are also passed, and in practice the ropes *c*⁴ are manipulated, as hereinafter described, to lower 70 and raise the life-boat.

The power-shaft *b*⁴ ranges transversely and inwardly of the deck of the vessel, and placed inwardly of the davit-shaft *b*² is the mechanism by which the shaft *b*⁴ and the boat-supporting ropes *c*⁴ are manipulated for operating the davits *c* to raise and lower the boat. This mechanism is mounted in a suitable framework *d*, comprising in the form of construction shown inner and outer plates or 80 member *d*² and *d*³, connected in any desired manner and into or through which the shaft *b*⁴ passes. The shaft *b*⁴ is provided within the casing or framework *d* with a pinion *b*⁶, as shown in Fig. 1, and mounted in said framework or casing over the shaft *b*⁴ is a crank-shaft *d*⁴, provided with a gear-wheel *d*⁵, which meshes with the pinion *b*⁶, and the said shaft *d*⁴ is provided in the form of construction shown and at either or both ends thereof with 90 a crank *d*⁶.

Mounted centrally of the framework or casing *d* is a drum-shaft *e*, provided with a drum *e*², divided centrally by a disk *e*³ into two separate parts, and the ropes *c*⁴, which operate the boat *c*⁵ and by which said boat is lowered and raised, are connected with the opposite end members of said drum, one of said ropes being secured to the bottom of one of said drum members and the other to the top of the other drum member, so that when the said drum is turned the said ropes will both be wound on or unwound from the drum, according to the direction in which the drum is turned.

The drum *e*² is provided at one end with a band or strap brake *e*⁴, (shown in full lines in Fig. 7, also in Fig. 1, and clearly indicated in dotted lines in Fig. 5,) and connected with the free end of said band or strap brake is a rod *e*⁵, part of which is screw-threaded, as shown at *e*⁶ in Fig. 6, and passed through a

threaded keeper e^7 , secured to the outer side member of the casing or framework d , and said rod is provided at its end with a crank-wheel or similar device e^8 , by which it may 5 be manipulated in the manner of other devices of this class.

The drum-shaft e is provided on the inner end portion thereof or at the end of the drum e^2 opposite the brake e^4 with a large gear-wheel f , and placed transversely of the frame or casing d over the drum e^2 is an eccentrically-mounted operating-shaft g , movable toward and from the drum e^2 , and which is mounted eccentrically in disks g^2 , which are 10 mounted in the opposite sides of the frame or casing d , said disks being provided at one side (the inner side as shown in the drawings) with flanges or rims g^3 and on the outer sides thereof with supplemental disks g^4 , 15 which are secured thereto. The disks g^2 are held in the sides of the frame or casing d by the flanges or rims g^3 at one side and the supplemental disks g^4 at the opposite sides thereof, and said supplemental disks g^4 are provided with radial arms g^5 , with which are 20 connected links g^6 , which are also connected with crank-arms g^7 , secured to a shaft i . An operating-shaft h is mounted in the framework or casing d parallel with the shaft g and 25 over the shaft i , and said shaft h is provided at one or both ends with a crank h^2 in the form of construction shown, and said shaft is also provided with a pinion h^3 , which meshes with a gear h^4 on the shaft g , and said 30 shaft g is also provided with a pinion h^5 , which meshes with the gear-wheel f on the drum e^2 or drum-shaft e .

The shaft i is mounted parallel with the shaft h and below the same in the form of 35 construction shown, and said shaft i is provided at one end with a crank-arm i^2 , and by means of the shaft i , which is operated by the arm i^2 , and the links g^6 and arms g^7 , connected with the disk g^2 , which are secured to the disks g^2 , it will be seen that by depressing the 40 arm i^2 the disks g^2 will be turned and the shaft g will be raised, so as to throw the pinion h^3 out of connection with the gear-wheel f , and by raising the arm i^2 this operation 45 will be reversed, and the shaft g will be thrown into gear with the drum, the pinion h^5 engaging the gear-wheel f .

In the accompanying drawings I have only 50 shown the operative mechanism of my improved apparatus, together with the boat c^6 ; but it will be understood that in practice a suitable cradle or support is provided for the boat, in which said boat normally rests and is secured in the usual manner, and the operation 55 will be readily understood from the foregoing description, when taken in connection with the accompanying drawings and the following statement thereof. If the boat be resting in its cradle (not shown) and it is desired to lower the same, the attaching de-

vices by which the boat is secured in the cradle are released, and the shaft h is turned to the right. This operation results in turning the shaft g and the drum e^2 and raising the boat out of its cradle. The shaft b^4 is then 70 turned to the left by means of the shaft d^1 , and this operation also turns the davit-shaft b^1 and swings the davits into the position shown in dotted lines in Fig. 1, in which the boat is freely suspended over and beyond the 75 side of the vessel. The brake e^4 may now be manipulated, so as to release the drum and allow it to turn freely, and in this operation the shaft i may also be turned, so as to throw the shaft g out of gear with the drum e^2 , and 80 the boat will drop freely into the water. It will be understood that this downward movement of the boat may be regulated as may be desired by means of the brake-rod e^5 , and it will also be understood that the shaft g need 85 not necessarily be thrown out of gear with the drum e^2 in this operation as the shafts h and i are free to revolve in the downward movement of the boat, if desired.

In order to raise the boat, if the shaft g 90 has previously been thrown out of gear with the drum e^2 said shaft is thrown back into gear with said drum by raising the arm i^2 of the shaft i , and the shaft h is then turned, so as to operate the drum and wind the ropes c^4 95 thereon, and when this operation has been fully completed and the boat raised to the desired height, as shown in full lines in Fig. 1, the brake e^4 is tightened, and the shaft b^4 is turned, so as to swing the davits and boat 100 into the position shown in full lines in Fig. 1, at which time the boat may be lowered into the cradle, (not shown,) as hereinbefore described.

The davits c are provided with chains j , 105 which are secured to the deck of the vessel at j^2 , and these chains are shown complete in dotted lines in Fig. 1 and shown partially in full lines in Figs. 1 and 9, and these chains form stays for the davits c and support and 110 strengthen them in their outboard position, as clearly shown in dotted lines in Fig. 1. I have also shown eyes or keepers k , which are secured to the deck of the vessel and through which the ropes c^4 are passed; but it will be 115 understood that in practice pulley-blocks may be employed for this purpose. The drum-shaft e is also provided at the outer end thereof with a ratchet m , and pivoted to the casing d at m^2 is a lever n , to which is pivoted 120 a pawl n^1 , which operates in connection with the ratchet m and is provided with a pin n^3 , movable in a slot n^4 in the head of the lever n , and said lever passes through a locking-keeper o and is adapted to be moved into different positions therein, in one of which the pawl n^1 engages the ratchet m and in the other of which said pawl is out of engagement with said ratchet, and the object of this construction is to provide means to prevent the 125 130

backward movement of the drum e^2 and to securely hold it at any desired point when the weight of the boat is suspended from the davits c by means of the ropes c^4 , and it will be understood that in the lowering of the boat, as hereinbefore described, the lever n must be operated, so that the pawl n^2 will not engage the ratchet m .

The brackets b , in which the davit-shaft b^2 is mounted, are provided with shoulders or projections p , and said davits c are provided with lugs or projections p , which strike against said shoulders and limit the outward movement of the davits when the latter are in the position shown in dotted lines in Fig. 1, but any suitable means may be provided for accomplishing this result.

In the accompanying drawings I have shown my improved apparatus designed to be operated by hand; but it will be apparent that any suitable power mechanism may, if desired, be provided for operating the drum e^2 , and various changes in and modifications of the construction herein shown and described may be made without departing from the spirit of my invention or sacrificing its advantages.

Having fully described my invention, what I claim as new, and desire to secure by Letters Patent, is—

1. In an apparatus of the class described, a horizontally-arranged davit-shaft, davits connected therewith and adapted to turn therewith, a transversely-arranged shaft geared in connection with said davit-shaft, a drum, ropes connected therewith and designed to support a boat from said davits, a shaft geared in connection with said drum and adapted to be thrown into and out of gear therewith, an operating-shaft geared in connection with the last-named shaft, and a brake connected with said drum, substantially as shown and described.

2. In an apparatus of the class described, a horizontally-arranged davit-shaft, davits connected therewith, a transversely-arranged shaft geared in connection with the davit-shaft, a crank-shaft geared in connection with the transversely-arranged shaft, a drum divided into two parts, ropes connected with the separate parts of the drum and adapted to support a boat from said davits, said ropes being adapted to be both wound on or both unwound from said drum according to the direction in which the latter is turned, and means for operating said drum, substantially as shown and described.

3. In an apparatus of the class described, a horizontally-arranged davit-shaft, davits connected with said shaft and adapted to turn therewith, means for limiting the movement of said shaft, a transversely-arranged shaft geared in connection with said davit-shaft, means for operating the transversely-arranged shaft, a drum divided into two

parts, ropes connected with the separate parts of said drum and arranged to suspend a boat from said davits, said ropes being adapted to be wound on or unwound from said drum according to the direction in which the drum is turned, and means for operating said drum, said drum being also provided with a brake, substantially as shown and described.

4. In an apparatus of the class described, a horizontally-arranged davit-shaft, davits connected with said shaft and adapted to turn therewith, means for limiting the movement of said shaft, a transversely-arranged shaft, a drum divided into two parts, ropes connected with the separate parts of said drum and arranged to suspend a boat from said davits, said ropes being adapted to be wound on or unwound from said drum according to the direction in which the drum is turned, and means for operating said drum, said drum being also provided with a brake and with a lock, substantially as shown and described.

5. In an apparatus of the class described, a davit-shaft, davits connected with said shaft and adapted to turn therewith, means for turning said davit-shaft, a drum divided into two parts, ropes connected with the separate parts of said drum and arranged to support a boat from said davits, and means for operating said drum, consisting of a shaft mounted parallel with said drum and geared in connection therewith and adapted to be thrown into and out of gear with said drum, and means for operating the last-named shaft, said drum being also provided with a brake and with a lock, substantially as shown and described.

6. In an apparatus of the class described, a horizontally-arranged davit-shaft, davits rigidly connected with said shaft and adapted to turn therewith, means for limiting the movement of said davit-shaft, a transversely-arranged shaft geared in connection with said davit-shaft, a power-shaft geared in connection with the transversely-arranged shaft, a drum mounted parallel with the power-shaft and transversely-arranged shaft and divided into two parts, ropes connected with the separate parts of said drum and arranged to suspend a boat from said davits, said ropes being adapted to be both wound on or unwound from said drum according to the direction in which the drum is turned, said drum being also provided with a brake and with a lock, and means for operating said drum.

7. In an apparatus of the class described, a horizontally-arranged davit-shaft, davits rigidly connected with said shaft and adapted to turn therewith, means for limiting the movement of said davit-shaft, a transversely-arranged shaft geared in connection with said davit-shaft, a power-shaft geared in connec-

tion with the transversely-arranged shaft, a drum mounted parallel with the power-shaft and transversely-arranged shaft and divided into two parts, ropes connected with the separate parts of said drum and arranged to suspend a boat from said davits, said ropes being adapted to be both wound on or unwound from said drum according to the direction in which the drum is turned, said drum being also provided with a brake and with a lock, and means for operating said drum, consisting of an eccentrically-mounted shaft movable toward and from and geared in connection with said drum, and a power-shaft 15 geared in connection with the eccentrically-mounted shaft.

8. In an apparatus of the class described, a horizontally-arranged davit-shaft, davits rigidly connected with said shaft and adapted to turn therewith, means for limiting the movement of said davit-shaft, a transversely-arranged shaft geared in connection with said davit-shaft, a power-shaft geared in connection with the transversely-arranged shaft, a 25 drum mounted parallel with the power-shaft

and transversely-arranged shaft and divided into two parts, ropes connected with the separate parts of said drum and arranged to suspend a boat from said davits, said ropes being adapted to be both wound on or unwound from said drum according to the direction in which the drum is turned, said drum being also provided with a brake and with a lock, and means for operating said drum, comprising a shaft mounted parallel therewith and geared in connection therewith and movable toward and from the drum, a power-shaft 30 geared in connection with the last-named shaft, and means whereby said last-named shaft may be moved toward and from the drum without breaking its connection with the power-shaft.

In testimony that I claim the foregoing as my invention I have signed my name, in presence of the subscribing witnesses, this 12th 45 day of January, 1906.

JOHN BOAG.
